UNITED STATES PATENT OFFICE.

SEYMOUR C. PALMER, OF SOUTH NORWALK, CONNECTICUT.

DIPPING APPARATUS FOR HAT-FORMING MACHINES.

SPECIFICATION forming part of Letters Patent No. 425,901, dated April 15, 1890.

Application filed October 4, 1888. Renewed February 12, 1890. Serial No. 340,154. (No model.)

To all whom it may concern:

Be it known that I, SEYMOUR C. PALMER, a citizen of the United States, residing at South Norwalk, in the county of Fairfield and State 5 of Connecticut, have invented certain new and useful Improvements in Dipping Apparatus for Hat-Forming Machines; and I do hereby declare the following to be a full, clear, and exact description of the invention, 10 such as will enable others skilled in the art to which it appertains to make and use the same.

My invention relates to certain improvements in hat-forming machines with the end 15 in view to facilitate the operation of dipping the hat-body in water; and it consists in the details of construction and combination of elements, such as will be hereinafter fully set forth, and then specifically designated by the 20 claim.

In the accompanying drawings, Figure 1 is 25 a side elevation of my improvement, and Fig. 2 a front elevation, the plunger-rod being broken away.

Similar letters denote like parts in both 30 figures.

In my pending application, filed in the United States Patent Office on the 24th day 35 of September, 1888, under Serial No. 286,147, I showed and described a hat-dipping apparatus in which the structure and operation of the hat-supporting means and the mechanism for operating to lower and elevate the rod P are precisely the same as in the instance of the present improvement, and I 40 therefore will enter into no detailed description of this means or mechanism, as they form no part of the present invention.

A is the tub containing water within which 45 the hat-body A' is to be dipped, and B are guide-lugs projecting from said tub.

C is the platform on which the cone is placed, and D is a bail secured at the ends to the platform and guided through the lugs B. 50 E E' are hangers; F, a counter-shaft journaled within said hangers; G, a pulley loose on said shaft and having a hub H, within which latter are formed notches a; I, a disk rigid on said shaft; J, a bolt extending loosely

through said disk and rendered resilient by 50 the action of a spring b, secured to said disk; K, an arm secured to the hanger E', and L is a detent pivoted to said arm and sustained in elevation by a coil-spring c, attached at its extremities to said arm and detent. The nose 55 of said detent is beveled, as seen at d, and is within the field of travel of the heel end of the bolt J, so that when said heel end is carried against the beveled nose the bolt will be withdrawn against the resiliency of the spring 60 b, and the said heel will be arrested by the stop-lug e at the base of the beveled nose.

All the parts hereinbefore set forth are the same with respect to construction and operation as are the similar parts shown and described in my aforesaid pending application. 65

M is a face-cam rigidly mounted on the shaft F.

N is a lever pivoted at the rear end to the hanger O, and P is a rigid rod pivoted at its 70 extremities to the forward end of the lever N and to the top of the bail, respectively.

Q is the cam-groove within the face-cam, and within this groove extends a pin R, which projects laterally from the lever N, so that it 75 will be seen that motion is communicated to the rod P from the cam-groove Q through the intermediate lever N. The contour and extent of the cam-groove are such with respect to the shaft F that a vertical reciprocation of variable speed will be imparted to the lever N and rod P, whereby the hat-body 80 A' on its cone will be properly dipped.

In my aforesaid pending application the 85 operation of the "crank-pin" within the slotted lever rendered the construction therein shown capable only of a limited variable motion, for the reason that during the fastest and slowest movements of the lever the "crank-pin" traveled in opposite directions 90 within the same section of the slot, thus necessarily limiting the fastest movement by the slowest, and vice versa. The present improvement obviates this disadvantage and greatly increases the capability of the apparatus, since the cam-groove is traversed but once by the pin R, and accordingly there is 95 no limit to the degree of variation of said

groove, and the very finest hats may be dipped within a given time and at any desired varying speed.

Having thus described my invention, what I claim as new, and desire to secure by Letters Patent, is—

The combination of the pivoted lever, the hat-supporting mechanism suspended therefrom, the face-cam rigidly mounted on a ro-

tary shaft, and the pin extending from said lever within the groove of said cam, substantially as set forth.

In testimony whereof I affix my signature in presence of two witnesses.

SEYMOUR C. PALMER.
